UNITED STATES PATENT OFFICE

2,478,450

CLOTHESLINE HOLDER

Otto Bahls, Brooklyn, N. Y.

Application December 18, 1946, Serial No. 716,951

1 Claim. (Cl. 211—119.07)

1

This invention relates to clothesline holders and has for its object to simplify the structure, and to provide a device for securely holding the holder in its inmost and outermost position.

The invention consists in the locking guide member for the holder, on the upper bracket, consisting of a U-shaped enclosure having a central hole at its bottom, for holding the horizontal portion of the rod of which the holder is constructed in its inner or outer position, the horizontal portion being raised from the U cavity to ride on the upper edge of the guide member while passing from one to the other position. The invention combines therewith a lower bracket and a coiled terminal portion on the lower end of the rod, to hold the line passing through the terminal.

The invention will be more fully described hereinafter, embodiments thereof shown in the drawings, and the invention will be finally pointed out in the claim.

In the accompanying drawings,

Fig. 1 is a perspective view of the improved device applied to a window frame, with the pulley in its inmost position;

Fig. 2 is a plan view taken on line 2—2 of Fig. 1;

Fig. 3 is an end view of Fig. 2;

Fig. 4 is a section taken on line 4—4 of Fig. 3, somewhat enlarged, and

Fig. 5 is a perspective view of the improved device, with the pulley in its outermost position.

Similar characters of reference indicate corresponding parts throughout the various views.

Referring to the drawings, the clothesline 10 is supported on two pulleys, one of which 11 is shown, other being on the usual pole (not shown). The frame 12 of the pulley 11 engages a hook shaped portion of a rod 13 extending inwardly of the room, which rod 13 has a bent corner 14 and then extends vertically downwardly, and is bent into a curved terminal portion 15, permitting the line or rope 10 to easily enter, be held therein, and be removed therefrom.

The window frame 16 supports by suitable bolts two brackets 18 and 19, vertically spaced from each other. The lower bracket 19, in the form shown, is a flat bar, twisted at its central portion, to enable one end to be parallel with the plane of the window frame and the other to be in a horizontal plane. This end 20 has an opening 21, for the passage of the vertical portion of the rod 13, in sliding engagement therewith.

The terminal portion 15 is spaced from this end 20 to permit the upward movement of the vertical portion of the rod 13, a certain distance.

The improvement consists in the structure of

the upper bracket 18. This, in the form shown, has a flat portion 23, in a vertical plane to enable it to be fastened to the window frame. This bar is then twisted as at 24, to form a horizontal platform 25. To this platform 25, there is secured by bolts 18a, a U-shaped guide member 26 having a rearward extension through which and through the platform 25, fastening bolts 18a pass. The bottom of the U has a hole 28 slightly larger in diameter than the diameter of the rod. When the pulley 11 is within the room, the horizontal part of the rod 13 rests in the U at the inner side of the guide member 26. The upper part of the line or rope 10 passes between the vertical part of the rod 13 and the window frame 16, and remains in the same relation when the pulley 11 is swung to its extreme outer position as shown in Fig. 5. The lower part of the line or rope 10 is free of the terminal 15 to enable the user to apply by means of clothespins the garments to be dried and then move them outwards, the pulley 11 being in its inward position. When a sufficient number of garments have been applied, and it is desired to close the window, the horizontal portion 13a of the rod 13 is raised until the bent corner portion rests on the guiding member, the rod 13 being moved on the pivot formed by the rod 13 passing through the hole 28, and the horizontal portion 13a rides on the upper edge 26a of the guide member 26 until the extreme outer part of the upper edge 26a is reached when the horizontal portion of the rod 13 drops into the U again and is locked thereby. Prior to moving the pulley 11 from its inmost position, the user passes the line or rope 10 into the terminal 15, and by the outward movement of the pulley 11, the lower part of the line is doubled on itself being bent at the terminal 15, as shown in Fig. 5.

The distance between the terminal and the lower bracket is determined by the amount of the distance corresponding to the required raising of the rod 13 from its U to the upper edge 26a.

When the garments are dried, the pulley 11 is moved from its outermost position to its innermost position, and the lower line is disengaged from the terminal 15. To so move the pulley, it is necessary to slightly raise the horizontal 13a until it rides on the upper edge, and until it drops into the U at its innermost end.

By the arrangement of the U-shaped guiding member 26 with the rod 13 passing through its opening 28, a very simple but very secure holding member is provided, which cooperates with the terminal to hold the line securely. By the mere

raising of the rod 13, it may be moved to either inward or outward position.

I have described several forms of my invention, but obviously various changes may be made in the details disclosed without departing from the spirit of the invention as set out in the following claim.

I claim:

In a clothesline holder having a line passing over spaced pulleys, the combination of a rod bent at right angles into a horizontal major and a vertical minor portion, a hook at the free end of the major portion connected to one of the pulleys, an open loop at the free end of the minor portion, with a pair of spaced brackets adapted to be secured to the window frame, one of said brackets having a U-shaped cup of a depth greater than the thickness of the horizontal rod, and having an opening receiving the vertical minor portion, the longitudinal axis of the cup being at right angles to the plane of the window frame, the lower bracket having an opening receiving the vertical minor portion of the rod, in

registration with the opening in the cup, and above said loop, and below the upper part of the line, whereby when the horizontal major portion is moved within the window frame for the application of the articles to be dried, it is held in position by the cup, and when moved outside of the window frame the major portion after riding on the upper edge of the cup is held in position by the cup, with the upper part of the line doubling on the vertical minor portion and the lower part of the line doubling on the loop.

OTTO BAHLS.
